G. C. SHEALY

WINDOW LOCK

Filed April 11, 1923

FIG. 2

INVENTOR

Grant C. Shealy
BY
G. F. Hinkel,
ATTORNEY

UNITED STATES PATENT OFFICE.

GRANT C. SHEALY, OF EAST CLEVELAND, OHIO.

WINDOW LOCK.

Application filed April 11, 1923. Serial No. 631,306.

To all whom it may concern:

Be it known that I, GRANT C. SHEALY, a citizen of the United States, and a resident of East Cleveland, county of Cuyahoga, and State of Ohio, have invented a new and useful Improvement in Window Locks, of which the following is a specification.

My invention relates to window locks.

The object of my invention is an efficient but simple window lock, economical of manufacture and of upkeep, easy to apply to existing windows, does not get out of order easily, locks and releases the window automatically, and effectively locks either part 10 of a window to the other after it is raised a certain distance and automatically unlocks the window when either of the parts is being closed. Other objects will appear during the description of the apparatus shown 15 in the drawing.

I attain these objects by the mechanism illustrated in the accompanying drawing in which Fig. 1 is a plan view of portions of an upper and a lower window with my lock 20 applied and shown in normal position ready to lock the windows or to permit them to move freely according to which way the window is moved; Fig. 2 is a section on line 2-2 of Fig. 1 clearly showing a side view 25 of my lock; Fig. 3 is a general perspective view showing more clearly a portion of the window structure and the relation of my lock thereto.

Similar reference characters refer to similar parts throughout the views.

It is quite desirable that windows be kept open a certain distance for suitable ventilation in homes etc., but it is also desirable that intruders may not enter through open 35 windows.

Therefore it is desirable that a lock be provided which locks the window in desired position.

In the accompanying drawing I have 45 shown my lock as applied to a window having a wood frame. It is quite obvious, however, that my lock may be applied to other kinds of windows as well as to other apparatus operating similar to the two parts 50 of the window shown.

Referring now particularly to the drawing.

The lock shown in the drawing consists of the stationary member A and the pivoted 55 member B.

The member A has the body portion 10

which is secured to the top of the lower part C of the window by means of the screws 11 and 12 and has the hinge-eyes 13 and 14.

This member A is very economically formed by cutting out the central portion of one end of a suitable plate and then bending the portions on each side of this cut out portion arcuately upward to form the hinge-eyes 13 and 14.

The member B has the body portion 15 and the hinge-eye 16 on one end thereof and a looped portion on the other end thereof. This loop portion consists of the upper 70 arcuate portion 17, the lower arcuate portion 18, the arcuate contact portion 19 eccentric with the hinge-pin 22 and connecting the portions 17 and 18, the flat portion 20 to form an abutment for the free end of 75 the loop for the purpose of preventing the loop from closing in connecting the portions 17 and 15, and the flat portion 21 abutting substantially at the juncture of portions 15 and 20.

The portion 19 is made arcuate and eccentric to provide increasing wedging action between the parts C and D when either of these parts is manipulated toward opening position while this portion 19 contacts 85 the part D.

This member B is also very economically formed by cutting away two portions at one end of a suitable plate and then bending the portion left in the center arcuately upward 90 to form the hinge-eye 16. The other end of the plate is then formed into the loop as shown. It is, of course, obvious that the loop may be formed first instead of first forming the hinge-eye.

It is noted that the hinge-eye 16 fits in between the hinge-eyes 13 and 14 and the previously mentioned cuts of both of the plates should be made accordingly before the bending operations begin so that no additional fitting is required when assembling the lock to the end that the cost of production is reduced to a minimum.

The hinge-pin 22 passes through the hinge-eyes 13, 14, and 16 and is, conveniently, riveted over on each end as is common in many hinges. A hinge-joint is thereby formed which permits the member B to move pivotally on the member A.

When installing this lock on a window as 110 shown in the drawing, the member A should be so located that the member B normally

extends inclinedly upward (as clearly seen in Fig. 2) when the two parts of the window are in normal position.

When it is desired to raise the lower part C to any desired height, the member B is swung left handedly (as viewed in Fig. 2) out of contact with the upper part D which permits of free movement up or down of the parts C or D.

- 10 When either of the parts C or D are moved to desired position, the member B is swung right handedly (as viewed in Fig. 2) until the portion 19 contacts the part D. The looped end of the member B may now 15 be pushed down slightly which movement locks the parts C and D to each other due to the wedging action exerted by the member B; then the part D can not be moved downward and the part C can not be moved 20 upward: therefore neither part of the window can be opened any further than originally intended without manipulating the lock which must be done from the inside.

It is not absolutely necessary that the 25 looped portion of the member B be pushed down as previously mentioned; it is sufficient that the looped end is swung so that the outer end thereof contacts the part D. Any attempt thereafter to either raise the part 30 C or lower the part D will cause this looped end to firmly grip and wedge the part D, due to the inclined installation of the member B, and wedge itself against the part D whereby a wedging action is created which 35 increases with the amount of pressure exerted on either the part C or D.

The downward movement of the part C, or the upward movement of the part D, or in other words, the closing of the window, 40 is not affected by the lock due to the inclined mounting of the member B which permits these movements of the parts C and D without wedging.

Therefore, a window provided with a lock 45 of the character described can be closed from the inside or from the outside without operating the lock, but cannot be opened either from the inside or the outside without operating the lock from the inside. This lock also prevents rattling of windows.

Having described my invention as now 50 contemplated,

I claim:—

- 55 1. A window lock comprising a stationary member, and a pivoted member having one end thereof hinged to said stationary member and the other end thereof provided with a loop having the end thereof abutting the

main body of this pivoted member to prevent closing in of this loop.

2. A window lock comprising a stationary member, and a pivoted member having one end thereof hinged to said stationary member and the other end thereof provided with a loop having an arcuate contact portion eccentric with said hinge joint and the end of this loop abutting the main body of this pivoted member to prevent closing in of this loop.

3. The combination of a window having 70 two parts adapted to slide over each other, and a lock comprising a stationary member secured to one of said window parts, and a pivoted member having one end thereof hinged to said stationary member and the 75 other end thereof provided with a loop having an arcuate contact portion eccentric with said hinge joint to provide increasing wedge action between said window parts during manipulation of either one or of both of said parts toward opening positions while this arcuate portion contacts the other of said parts.

4. The combination of a window having a lower part and an upper part adapted to 85 slide over each other, and a lock comprising a stationary member secured to said lower part, and a pivoted member having one end thereof hinged to said stationary member and the other end thereof provided with a 90 loop having an arcuate contact portion eccentric with said hinge joint and adapted to contact said upper part to provide increasing wedge action between said parts during manipulation of either one or of both 95 of said parts toward opening positions while this arcuate portion contacts said upper part.

5. The combination of a window having a lower part and an upper part adapted to 100 slide over each other, and a lock comprising a stationary member secured to said lower part, and a pivoted member having one end thereof hinged to said stationary member and the other end thereof provided with a 105 loop having an arcuate portion eccentric with said hinge joint and adapted to contact said upper part to provide increasing wedge action between said parts during manipulation of either one or of both of said parts toward opening positions, and the end of said loop abutting the main body of said pivoted member to prevent closing in of said loop.

GRANT C. SHEALY.
